UNITED STATES PATENT OFFICE.

MICHAEL WILLIAM LAWLOR, OF NEEDHAM HEIGHTS, MASSACHUSETTS.

POULTRY-FEEDER.

1,038,766.

Specification of Letters Patent. Patented Sept. 17, 1912.

Application filed December 28, 1911. Serial No. 668,243.

To all whom it may concern:

Be it known that I, MICHAEL WILLIAM LAWLOR, a citizen of the United States, residing at Needham Heights, in the county 5 of Norfolk and State of Massachusetts, have invented certain new and useful Improvements in Poultry-Feeders, of which the following is a specification.

This invention relates to that class of 10 poultry feed devices in which the supply is controlled by the fowls, the purpose of the arrangement being to compel the fowls to exercise.

It is the object of the invention to provide 15 a simple and efficient device of the kind stated, and also one in which the grain is freely discharged and all danger of clogging up of the device is obviated.

With these objects in view, the invention 20 consists in a novel construction and arrangement of parts to be hereinafter described and claimed.

In the accompanying drawing forming a part of this specification, Figure 1 is a perspective view showing the application of the 25 invention. Fig. 2 is an elevation, partly in section, of the discharge device. Fig. 3 is an elevation showing a modified form of discharge device.

Referring specifically to the drawing, 30 5 denotes a suitable receptacle which holds the supply of grain or other feed. The receptacle is supported on legs 6; or it may be hung up, a bail 7 being provided for this purpose. The receptacle has a hopper bottom, and to the outlet thereof is connected a screw-threaded nipple 8.

The device which controls the discharge 40 9 of the grain from the receptacle is a tube which depends from the nipple 8. The tube is a coil of wire similar to a helical spring. The convolutions of the coil are brought close together to prevent the grain from passing therebetween when the coil is 45 in its normal position. At the bottom of the coil the convolutions are spread apart sufficiently to enable the fowl to pick out the grain. The bottom of the coil is closed by a plug 10, and its upper end is open and 50 screws over the nipple 8. The grain therefore drops from the receptacle into the coil and is held therein until it is stretched sufficiently to let the grain pass out between the convolutions. The plug 10 carries a rod

11 which extends centrally and lengthwise 55 through the coil and enters the receptacle, said rod serving to stir up the grain and thereby prevent clogging. Instead of closing the lower end of the coil by a plug 10, the closure may be made by gradually decreasing the diameter of the convolutions, as shown in Fig. 3.

In operation, the fowls jump for the grain in sight at the lower end of the coil, and in so doing pull the coil down and spread 65 the convolutions thereof so that the grain drops out and is scattered in every direction. The fowls are therefore given exercise, and waste of grain is also prevented. The movement of the coil operates the rod 70 11 and the latter causes the grain to feed evenly and prevents it from clogging the coil.

The device herein described is simple in construction, and can therefore be cheaply 75 manufactured, and it effectually serves the purpose for which it is designed. No specially constructed receptacle is necessary.

I claim:

1. A poultry feeder comprising a receptacle, and a depending discharge tube connected thereto, said tube comprising a helical coil which is closed at its lower end, and has its lower convolutions permanently spaced apart to permit escape of the feed. 80

2. A poultry feeder comprising a receptacle, a depending discharge tube connected thereto, said tube comprising a helical coil which is closed at its lower end, and has its lower convolutions permanently spaced 90 apart to permit escape of the feed, and an agitator carried by the coil and extending therethrough into the receptacle.

3. A poultry feeder comprising a receptacle having a threaded nipple at its outlet, 95 and a depending discharge tube connected to the nipple, said tube comprising a helical coil which is closed at its lower end and screws at its upper end on the nipple, said coil having its lower convolutions permanently spaced apart to permit escape of the feed. 100

In testimony whereof I affix my signature in presence of two witnesses.

M. WILLIAM LAWLOR.
